PROCESS FOR PRODUCTION OF OLEFINS BY
DIMERIZATION, CO-DIMERIZATION, POLYM-
ERIZATION AND CO-POLYMERIZATION OF
OLEFINS

Olav-Torgeir Onsager, Baerum, Norway, assignor to

ABSTRACT OF THE DISCLOSURE

Monolefins are oligomerized using a catalyst mixture comprising a cyclobutadiene nickel dihalide and a compound such as ethylaluminum dichloride or diethylberyllium to give a product with a high content of beta- and gamma-olefins. The use of ethylene and/or propylene as the feed with tetramethylcyclobutadiene-nickel-dichloride or tetraphenylcyclobutadiene-nickel-dichloride as a catalyst component is illustrated.

By the development of cracking processes in the modern petroleum industry the low-molecular alpha-olefins, such as ethane, propene and butene, have become easily available raw materials on a large industrial scale.

Besides the direct utilization in the production of high-molecular compounds in the plastic industry, the refining processes of these raw materials to products in the range C₄—C₃₀ play an important part in industrial, organic chemistry.

It is known that beryllium, aluminium, gallium and indium compounds of the types BeR₂, AlR₃ and InR₃, in which at least one of the ligands, R, represents an organic hydrocarbon residue of hydrogen, are able to convert lower olefins to dimerized, trimerized and higher products with high alpha-olefine content, and that the presence of finely powdered metallic cobalt, nickel or platinum increases the selectivity of the systems favouring the formation of more low-molecular (dimerized) products. In particular, finely powdered metallic nickel in the form of Raney nickel additions or metallic nickel reduced from nickel compounds by conversion with a certain amount of the organic main group metal component at higher temperature, has been used. In order to prevent the metallic nickel component from being inactivated during an early phase of the synthesis, processes have been developed in which acetylene or hydrocarbons with acetylene bonds are added during the conversions. In the polymerization of ethane with aluminium-trialkyl and metallic nickel as catalyst, the minimum amount of acetylene which is added is reported to lie in the range 0.2–1% of the total quantity of converted ethene (German Patent No. 1,001,981).

Drawbacks of the known oligomerization processes of the Ziegler type, besides the additions of the types of organic compounds described above are, that these processes use very high catalyst concentrations of the main group metal compound, up to 20% of the reaction mixture. Also, due to the high temperatures and pressures which are required during the syntheses, up to 250° C./200 atm. (German Patent No. 964,642, U.S. Patent No. 2,695,327), vary inflammable and explosive mixtures are produced.

A characteristic feature of the said processes, in which transitional metal additions are used as co-catalyst, is that these exist in finely powdered metallic form with the formation of a heterogenous phase in the catalytic mixtures.

2

Surprisingly we have now found that cyclodiene-nickel-dihalides, which in combination with metal-organic compounds of the metals in 2nd and 3rd main group in the periodic table are not reduced to metallic nickel, and which in mixtures with the main group metal compounds mentioned above represented very active catalyst systems for dimerization, co-dimerization, polymerization and co-polymerization of alpha-olefines from the range C₂—C₁₅ at such mild conditions as, for example, 20° C./1 atm., under formation of mono-olefines in the range C₄—C₃₀ with high content of beta- and gamma-olefines.

As the main group metal component there can be used one or more compounds of the types Be(R)_a(Y)_{2-a}, 15 Al(R)_b(Y)_{3-b}, Ga(R)_b(Y)_{3-b} and In(R)_b(Y)_{3-b} and/or their adition compounds with electrondonor compounds such as ethers, phosphines etc., in which R=hydrocarbon radical, preferably alkyl and/or hydrogen, Y=acid radical, such as halogen and alkoxy-groups, a=1–2 and b=1–3.

From the literature it is known that organic ligands, preferably such containing one or more carbon/carbon double or triple bonds, can be attached to a transition metal by electronic interactions between the p-electrons 25 of the ligand and the d-electrons of the transition metals or free d-electron orbitals (π -bonds). Compounds which contain such types of bonds are termed π -organic transition metal compounds. Common to the types of organic nickel compounds indicated above is that these contain 30 π -bonded organic ligands. Since other nickel organic compounds containing the same type of bond satisfying the necessary stability requirements exist in addition to the above-mentioned types of π -organic nickel compounds, active catalyst components will also be found 35 among these compounds.

The advantage of the process according to the invention is that use is made of a soluble catalyst having such high activity that the reactions can take place at substantially lower temperature, pressure and catalyst concentration than those described as favourable in formerly known oligomerization processes of the Ziegler type. Besides, the composition of the reaction products differs at essential points from the above mentioned types of processes by the fact that there are formed dimerized 40 and trimerized mono-olefines with very high content of beta- and gamma-olefines. The formation of the active catalyst system is very simple. It occurs automatically at the mixing of the two types of catalyst components, advantageously in the form of solutions in an inert organic solvent, such as benzene, xylene, heptane or higher paraffins, in argon or nitrogen atmosphere. The concentration of the main group metal compound, as well as the relative proportion of the two types of compound, can be varied within wide limits. It has been found favourable to the process to use main group metal concentrations 45 within the range 0.001–0.100 mole/liter, and a nickel-main group metal molar ratio in the range 1:1–0.01:1.

The process according to the invention can be performed at pressures from fractions of an atmosphere up to 60 very large pressures, limited only by the apparatus construction. It is, however, advantageous, out of regard for temperature control, that the reactions take place at pressures not exceeding 100 atm. The reducing effect which lies in the main group metal-carbon bonds Be—C, Al—C, Ga—C and In—C may lead to a reduction of the nickel compounds, if the temperature during the conversion is 65 too high. The reaction temperature should therefore be kept below the temperature range in which a substantial part of the nickel compound in the course of the conversion is destroyed by reduction to metallic nickel, preferably not exceeding 100° C. The highest reaction temperatures can be selected in the processes which make 70

use of the most stable cyclobutadiene nickel compounds in combination with the least reduction-active main group metal compounds as catalysts.

The process can be carried out either discontinuously, for example, by placing the catalyst components together with a solvent, if necessary, in a thermostat-regulated reaction vessel, passing the monomer or the monomer mixture for some time, e.g. 1-5 hours, into the catalyst mixture, and then extracting the reaction product by the usual working methods, or continuously, for example by passing the monomer or the monomer mixture through the catalyst mixture, with subsequent continuous isolation of the reaction product from the outflowing gas mixture. Unreacted monomer and solvent, if any, and catalyst are separated from the reaction product during the isolation of the latter and are suitably recirculated to the reaction vessel. By the process according to the invention, in which the monomer is a liquid, solvent can be omitted with advantage. In addition to the alpha-olefines, mixtures of their isomeric compounds may also be used as raw material for the processes, due to the isomerization activity of the catalyst systems.

APPARATUS AND TECHNIQUE

For the examples 1-9 the following apparatus and work technique were used:

One or more of the above-mentioned types of nickel compounds are placed in a thermostat-regulated glass reaction flask, equipped with a magnetic stirrer, reflux condenser and dropping funnel with pressure-equalizing means. On the top of the reflux condenser there was a possibility of connection to vacuum, highly purified nitrogen and highly purified starting-monomer for the syntheses. The apparatus was evacuated for 1 hour, then filled with nitrogen. In the course of the nitrogen flushing the desired quantity of abs. solvent was added to the reaction flask. A main group metal compound of the above-mentioned type or mixtures of these are, if necessary diluted with solvent, then added to the dropping funnel in a nitrogen atmosphere. The whole apparatus is then carefully evacuated three times and after each time filled with the starting-monomer at atmospheric pressure. At reaction time zero the two catalyst components, each saturated with the starting-monomer, are mixed under agitation in the reaction flask. The inflow velocity of the starting-monomer required to maintain constant pressure in the reaction flask (1 atm.) was measured with a capillary flow meter as a function of reaction time. The bath temperature was kept constant within the limits $\pm 0.05^\circ$ C. by means of a water-circulation thermostat. After a certain reaction time the conversion was stopped and the reaction mixture was gas-chromatographically analyzed.

For the Examples 10-13 the following apparatus and technique were used:

The reactions were carried out in a non-magnetic, acid-resistant steel autoclave having a volume of 200 ml. The autoclave was connected with a glass container which could be evacuated. The connection between the two vessels could be closed by means of a high pressure valve. Before the experiment the autoclave and glass container were evacuated to less than 0.5 mm. Hg in 30 min. The valve between the two vessels was closed and the glass container filled with highly purified nitrogen. The catalyst components and the solvent were then poured into the glass container in a nitrogen atmosphere.

By opening the valve between the two vessels the catalyst solution was sucked into the evacuated autoclave. The connection to the vacuum pump was cut off in advance. The autoclave was then filled with monomer to the indicated pressure, which was kept constant during the whole reaction period. The autoclave was fitted with a magnetic stirrer and placed in a water bath with the stated temperatures $\pm 0.1^\circ$ C. The reaction mixtures were gas-chromatographically analyzed.

EXAMPLE 1

Temperature: 28° C. Pressure: 1 atm. Solvent: 44 g. benzene. Catalyst: 35.7 mg. tetramethylcyclobutadiene-nickel-dichloride, 127 mg. aluminium-monoethyl-dichloride. Monomer: ethene. Reaction time: 60 min. Reaction product formed: 15 g. Composition of product: 78% C₄-olefines (of which 1.3% butene-1, 72.6% butene-2-trans and 26.1% butene-2-cis).

17% C₆-olefines (of which 20% hexene-3-cis and trans, 55% hexene-2-trans, 14% hexene-2-cis and 11% 3-methyl-pentene-2-cis and trans). 5% higher than C₆-olefines.

EXAMPLE 2

15 Temperature: 20° C. Pressure: 1 atm. Solvent: 44 g. benzene. Catalyst: 119 mg. tetramethylcyclobutadiene-nickel-dichloride, 127 mg. aluminium-monoethyl-dichloride. Monomer: propene. Reaction time: 60 min. Reaction product formed: 20 g.

20 Composition of product: 95% C₆-olefines (of which 0.9% 4-methylpentene-1, 2.8% 4-methylpentene-2-cis, 23.1% 4-methyl-pentene-2-trans, 3.6% 2-methylpentene-1, 42.5% 2-methyl-pentene-2, 4.4% hexene-3-cis and trans, 13.6% hexene-2-trans, 4.7% hexene-2-cis and 4.4% 2,3-dimethylbutene-2). 5% higher than C₆-olefines.

EXAMPLE 3

30 Temperature: 20° C. Pressure: 1 atm. Solvent: 44 g. benzene. Catalyst: 35.7 mg. tetramethylcyclobutadiene-nickel-dichloride, 127 mg. aluminium-monoethyl-dichloride. Monomer: ethene/propene = 1/4 (gas volume at 20° C./1 atm.). Reaction time: 30 min. Reaction product formed: 9 g.

35 Composition of product: 2% C₄-olefines (of which, 72.7% butene-2-trans, 27.3% butene-2-cis). 28% C₅-olefines (of which, 1.0% 2-methylbutene-1, 5.5% 2-methylbutene-2, 72.4% pentene-2-trans, 21.1% pentene-2-cis). 65% C₆-olefines (of which, 1.5% 4-methylpentene-1, 7.3% 4-methylpentene-2-cis, 52.4% 4-methylpentene-2-trans, 4.8% hexene-3-cis and trans, 17.5% hexene-2-trans, 12.7% 2-methylpentene-2 and 3.8% hexene-2-cis). 5% C₇-olefines.

EXAMPLE 4

45 Temperature: 20° C. Pressure: 1 atm. Solvent: 37 g. benzene. Catalyst: 30 mg. tetramethylcyclobutadiene-nickel-dichloride, 180 mg. aluminium - monoethyl - dibromide. Monomer: ethene. Reaction time: 60 min. Reaction product formed: 2.3 g. Composition of product: 80% C₄-olefines (of which approx. 100% butene-2-trans). 15% C₆-olefines (of which 31% hexene-3-trans, 69% hexene-2-trans). 5% higher than C₆-olefines.

EXAMPLE 5

55 Temperature: 20° C. Pressure: 1 atm. Solvent: 40 g. benzene. Catalyst: 30 mg. tetramethylcyclobutadiene-nickel-dichloride, 115 mg. dialuminium-triethyl-monoethoxy-dichloride. Monomer: ethene. Reaction time: 120 min. Reaction product formed: 7.5 g.

60 Composition of product: 82.1% C₄-olefines (of which 1.8% butene-1, 70.0% butene-2-trans, 28.2% butene-2-cis). 14.9% C₆-olefines (of which 6.7% hexene-3-cis and trans, 3.1% 2-ethylbutene-1, 18.3% hexene-2-trans, 20.1% 3-methylpentene-2-trans, 6.7% hexene-2-cis and 45.1% 3-methylpentene-2-cis). 3% higher than C₆-olefines.

EXAMPLE 6

70 Temperature: 20° C. Pressure: 1 atm. Solvent: 44 g. benzene. Catalyst: 35.7 mg. tetramethylcyclobutadiene-nickel-dichloride, 217 mg. aluminium-diphenyl-monochloride + 131.2 mg. triphenylphosphine. Monomer: ethene. Reaction time: 180 min. Reaction product formed 4.5 g.

75 Composition of product: 97% C₄-olefines (of which 9.2% butene-1, 62.5% butene-2-trans, 28.3% butene-2-cis). 3% higher than C₆-olefines.

EXAMPLE 7

Temperature: 20° C. Pressure: 1 atm. Solvent: 44 g. benzene. Catalyst: 119.0 mg. tetramethylcyclobutadiene-nickel-dichloride + 131.2 mg. triphenylphosphine, 34 mg. berylliumdiethyl (added in this order). Monomer: ethene. Reaction time: 30 min. Reaction product formed: 5 g.

Composition of product: 91% C₄-olefines (of which 2.4% butene-1, 69% butene-2-trans, 28.6% butene-2-cis), 8% C₆-olefines (of which 29.2% hexene-3-+ 2-ethylbutene-1, 20.2% hexene-2-trans, 18.0% 3-methylpentene-2-trans, 32.6% 3-methylpentene-2-cis). 1% higher than C₆-olefines.

EXAMPLE 8

Temperature: 20° C. Pressure: 1 atm. Solvent: 44 g. benzene. Catalyst: 75 mg. tetramethylcyclobutadiene-tri-phenylphosphine-nickel-dichloride, 127 mg. aluminium-monoethyl-dichloride. Monomer: ethene. Reaction time: 30 min. Reaction product formed: 4 g.

Composition of product: 46.6% C₄-olefines (of which 2% butene-1, 69.5% butene-2-trans and 28.5% butene-2-cis), 48.4% C₆-olefines (of which 4.0% hexene-3-cis and trans, 7.0% 2-ethylbutene-1, 9.0% hexene-2-trans, 26.0% 3-methylpentene-2-trans, 4.0% hexene-2-cis, 50% 3-methylpentene-2-cis). 5% higher than C₆-olefines.

EXAMPLE 9

Temperature: 20° C. Pressure: 1 atm. Solvent: 44 g. benzene. Catalyst: 43.8 mg. tetraphenylcyclobutadiene-nickel-dichloride, 127 mg. aluminium-monoethyl-dichloride. Monomer: ethene. Reaction time: 30 min. Reaction product formed: 5 g.

Composition of product: 72% C₄-olefines (of which 7.5% butene-1, 67.3% butene-2-trans, 25.2% butene-2-cis), 26% C₆-olefines (of which 12.2% hexene-3-cis and trans, 25.1% hexene-2-trans, 15.5% 3-methylpentene-2-trans, 7.4% hexene-2-cis, 39.8% 3-methylpentene-2-cis). 2% higher than C₆-olefines.

EXAMPLE 10

Temperature: 25° C. Pressure: 5 atm. Solvent: 44 g. benzene. Catalyst: 29.8 mg. tetramethylcyclobutadiene-nickel-dichloride, 190 mg. aluminium-monoethyl-dichloride + 196.5 mg. triphenylphosphine. Monomer: propene. Reaction time: 60 min. Reaction product formed: 35 g.

Composition of product: 92% C₆-olefines (of which 1.5% 4-methylpentene-1, 4.8% 4-methylpentene-2-cis, 23.0% 4-methyl-pentene-2-trans, 9.3% 2-methylpentene-1 and hexene-1, 4.7% hexene-3-cis and trans, 13.1% hexene-2-trans, 37.1% 2-methyl-pentene-2, 3.9% hexene-2-cis and 2.6% 2,3-dimethylbutene-2). 8% higher than C₆-olefines.

EXAMPLE 11

Temperature: 50° C. Pressure: 5 atm. Solvent: 34.2 g. heptane. Catalyst: 50.5 mg. tetramethylcyclobutadiene-nickel-dichloride, 254 mg. aluminium-monoethyl-dichloride. Monomer: propene. Reaction time: 60 min. Reaction product formed: 40 g.

Composition of product: 72.5% C₆-olefines (of which 2.3% 4-methylpentene-1, 6.3% 4-methylpentene-2-cis, 36.5% 4-methyl-pentene-2-trans, 2.1% 2-methylpentene-1 and hexene-1, 5.2% hexene-3-cis and trans, 16.9% hexene-2-trans, 23.0% 2-methyl-pentene-2, 5.3% hexene-2-cis, 2.4% 2,3-dimethylbutene-2). 27.5% higher than C₆-olefines.

EXAMPLE 12

Temperature: 0° C. Pressure: 41 atm. Solvent: 44 g. benzene. Catalyst: 35.7 mg. tetramethylcyclobutadiene-nickel-dichloride, 127 mg. aluminium-monoethyl-dichloride. Monomer: ethene. Reaction time: 60 min. Reaction product formed: 70 g.

Composition of product: 60% C₄-olefines (of which 7.0% butene-1, 65.5% butene-2-trans, 27.5% butene-2-cis), 30% C₆-olefines (of which 1.5% 3-methylpentene-1,

0.7% hexene-1, 12.0% hexene-3-cis and trans, 10.6% 2-ethylbutene-1, 22.0% hexene-2-trans, 13.6% 3-methylpentene-2-trans, 8.0% hexene-2-cis, 31.6% 3-methylpentene-2-cis). 10% higher than C₆-olefines.

EXAMPLE 13

Temperature: 85° C. Pressure: 5 atm. Solvent: 44 g. benzene. Catalyst: 59.5 mg. tetramethylcyclobutadiene-nickel-dichloride, 254 mg. aluminium-monoethyl-dichloride. Monomer: propene. Reaction time: 60 min. Reaction product formed: 7 g.

Composition of product: 63% C₆-olefines (of which 0.8% 4-methylpentene-1, 4.2% 4-methylpentene-2-cis, 24.1% methylpentene-2-trans, 0.5% 2-methylpentene-1 and hexene-1, 8.8% hexene-3-cis and trans, 24.6% hexene-2-trans, 25.3% 2-methylpentene-2, 6.7% hexene-2-cis, 5.0% 2,3-dimethylbutene-2). 27% higher than C₆-olefines.

I claim:

1. In a process for the production of monoolefines in the range of C₄-C₃₀ by the catalytic conversion of olefins in the range of C₂-C₁₅, the improvement according to which the catalyst is a catalytic mixture of one or more cyclobutadiene nickel dihalides and one or more compounds selected from the group consisting of

Be(R)_a(Y)_{2-a}

and Me(R)_b(Y)_{3-b}, in which R is selected from the group consisting of hydrocarbon radicals and hydrogen, Y is an acid radical, a is a number from 1 to 2, b is a number from 1 to 3, and Me is selected from the group consisting of Al, Ga and In.

2. The improvement according to claim 1 wherein the cyclobutadiene nickel dihalides are employed as addition compounds with electron-donor components.

3. The improvement according to claim 1, wherein the compounds selected from the group consisting of

Be(R)_a(Y)_{2-a}

and Me(R)_b(Y)_{3-b} are employed as addition compounds with electron-donor components.

4. The improvement according to claim 1, wherein both the cyclobutadiene nickel dihalides and the compounds selected from the group consisting of

Be(R)_a(Y)_{2-a}

and Me(R)_b(Y)_{3-b} are employed as addition compounds with electron-donor components.

5. In a process for the production of monoolefines in the range of C₄-C₃₀ by the catalytic conversion of olefins in the range of C₂-C₁₅, the improvement according to which the catalyst is a catalytic mixture of one or more cyclobutadiene nickel dihalides and one or more compounds selected from the group consisting of Be(R)_a(Y)_{2-a} and Me(R)_b(Y)_{3-b}, in which R is selected from the group consisting of alkyl and aryl, Y is selected from the group consisting of halogen and alkoxy, a is a number from 1 to 2, b is a number from 1 to 3, and Me is selected from the group consisting of Al, Ga and In.

6. The improvement according to claim 5, wherein the cyclobutadiene nickel dihalides are used as addition compounds with electron-donor components.

7. The improvement according to claim 5, wherein the compounds selected from the group consisting of

Be(R)_a(Y)_{2-a}

and Me(R)_b(Y)_{3-b} are employed as addition compounds with electron-donor components.

8. The improvement according to claim 5 wherein the cyclobutadiene nickel dihalides and the compounds selected from the group consisting of Be(R)_a(Y)_{2-a} and

Me(R)_b(Y)_{3-b}

are used as addition compounds with electron-donor components.

9. In a process for the production of monoolefines in the range of C₄-C₃₀ by the catalytic conversion of olefins

in the range of C_2 — C_{15} , the improvement according to which the catalyst is a catalytic mixture of one or more cyclobutadiene-nickel-dihalides and one or more aluminiumalkylhalides.

10. The improvement according to claim 9 wherein the cyclobutadiene-nickel-dihalides are used as addition compounds with electron-donor components.

11. The improvement according to claim 9 wherein the aluminium-alkylhalides are used as addition compounds with electron-donor components.

12. The process according to claim 9 wherein the cyclobutadiene-nickel-dihalides and the aluminium-alkylhalides are used as addition compounds with electron-donor components.

13. In a process for the production of monoolefines in the range of C_4 — C_{30} by the catalytic conversion of ethene and propene at a temperature of up to 100° C. and at a pressure of up to 100 atmospheres, the improvement according to which the catalyst is a catalytic mixture of cyclobutadiene-nickel-dihalides, and an aluminium-alkylhalide.

14. The improvement according to claim 13 wherein the cyclobutadiene-nickel-dihalides are used as addition compounds with triphenyl phosphine.

15. The improvement according to claim 13 wherein the aluminium-alkylhalide is used as an addition compound with triphenyl phosphine.

16. The improvement according to claim 13 wherein the cyclobutadiene-nickel-dihalides and the aluminium-alkylhalide are used as addition compounds with triphenyl phosphine.

17. In a process for the production of mono-olefines in the range of C_4 — C_{30} by the catalytic conversion of ethene and propene at a temperature of up to 100° C. and at a pressure of up to 100 atmosphere, the improvement

5

10

15

20

25

30

35

according to which the catalyst is a catalytic mixture of a cyclobutadiene nickel-compound selected from the group consisting of tetramethylcyclobutadiene-nickeldichloride, and tetraphenylcyclobutadiene-nickeldichloride, and a main group metal compound selected from the group consisting of aluminium-monoethyl-dichloride, aluminium-monoethyl-dibromide, aluminium-diphenyl-monochloride, dialuminium - triethylmonoethoxy - dichloride and berylium-diethyl.

18. The improvement according to claim 17, wherein the cyclobutadiene nickel compound is used as an addition compound with triphenyl phosphine.

19. The improvement according to claim 17 wherein the main group metal compound is used as an addition compound with triphenyl phosphine.

20. The improvement according to claim 17 wherein the cyclobutadiene nickel compound and the main group metal compound are used as addition compounds with triphenyl phosphine.
